MAN'S VEST

Mary Bello, Brooklyn, N. Y.

Application May 14, 1938, Serial No. 207,936

3 Claims. (Cl. 2—102)

This invention relates to new and useful improvements in men's vests.

More specifically, the invention proposes the construction of a man's vest which is characterized by the provision of a combination shirt and vest front which when worn with street clothes appears to be of conventional construction, but in reality consists only of the shirt front and vest front, and a means for holding the same upon the body.

Still further it is proposed to construct the vest as a formal vest, a tuxedo shirt front; a shirt front, or a combination shirt and vest front according to this invention.

15 A further object of this invention is to provide a belt portion for engaging the waist of a wearer and attached at the sides with said vest front for holding the bottom portion of said vest in position.

20 For further comprehension of the invention, and of the objects and advantages thereof, reference will be had to the following description and accompanying drawing, and to the appended claims in which the various novel features of the invention are more particularly set forth.

25 In the accompanying drawing forming a material part of this disclosure:

Fig. 1 is an elevational view of a formal vest constructed according to this invention.

30 Fig. 2 is a rear elevational view of Fig. 1.

Fig. 3 is a sectional view on the line 3—3 of Fig. 1.

Fig. 4 is a view looking in the direction of the line 4—4 of Fig. 3.

35 Fig. 5 is an elevational view of a tuxedo shirt front constructed according to this invention.

Fig. 6 is a perspective view of a shirt front "junior" constructed according to this invention.

Fig. 7 is a rear elevational view of Fig. 6.

40 Fig. 8 is an elevational view of a shirt front "senior" constructed according to this invention.

Fig. 9 is a rear elevational view of Fig. 8.

Fig. 10 is an elevational view of a shirt front vest constructed according to this invention.

45 Fig. 11 is a partial rear elevational view of a vest constructed according to a still further modification of the invention.

Fig. 12 is a sectional view on the line 12—12 of Fig. 11.

50 The man's vest, according to this invention, is a combination garment comprising a garment front for extending from the neck to the waist along the front of the body and openable from the neck down along its center. The garment further comprises a tuxedo shirt front 10 having

lapel portions 10^a and to which a portion of a formal shirt 11 is attached. This formal shirt portion 11 is securely attached to the edges of the formal vest 10 by means of stitches 12. It is the formal shirt 11 which is open along its center 11^a for permitting the garment to be placed upon the body. This opening is adapted to be closed by buttons or shirt studs 13.

The neck portion 11^b of the shirt front portion 11 is adapted to extend around the neck for 10 supporting the top portion of the vest upon the body. This neck portion is in the form of a conventional formal collar and is attached to the top portion of the vest. A belt portion 14 is securely attached at one side to one edge portion of the 15 vest 10 and is adapted to extend around the waist in position upon the body.

A slide fastener 15 is provided for releasably connecting the free end of the belt portion 14 20 to the free edge of the form vest 10 for securely attaching this portion to the vest. A back panel 16 is formed integrally with the neck portion 11^b and extends across one's back and is connected at its bottom end to a portion of the belt portion 14 by means of stitches 17. Thus when the form vest, constructed according to this invention, is positioned upon the body and a formal coat is worn therewith the vest gives the appearance of a formal shirt and a formal vest, 30 but in reality it is a combination formal vest portion and formal shirt portion.

According to the modification shown in Fig. 5 the garment front consists of a vest portion 18 having a shirt portion 19 attached thereto in a 35 manner similar to that described relative to Fig. 1. A neck portion 19^b consisting of a slightly differently shaped collar is attached to the shirt front 19 and is adapted to extend around the neck. The rear view of this garment is similar 40 to that shown in Fig. 2. The difference between the garments is that the one shown in Fig. 1 is the formal vest while the one in Fig. 5 is a tuxedo shirt front and has the vest and collar formed slightly different.

According to the modification shown in Figs. 6 and 7 the garment front consists of a conventional shirt front 20 which is open from the neck to the waist and is adapted to be closed by buttons 21. A neck portion 20^b consisting of a conventional collar is attached to the top portion of the shirt front 20 and is adapted to extend around one's neck. A belt portion 22 is attached to the bottom edge of the shirt front 20 and is adapted to extend around the waist and to have 55

its adjacent edges closed by a slide fastener 23. An elastic insert 24 is inserted into a portion of the belt portion 22 and is adapted to resiliently urge the belt portion into a position in which it will rigidly support the shirt front.

According to the modification shown in Figs. 8 and 9 a shirt front 25 of conventional construction is open from the neck to the waist and is provided with buttons 26 for closing this opening. A neck portion 25a in the form of a conventional collar is adapted to extend around one's neck.

A back panel 25b extends from the top of the shirt front 25 and passes to the back of the body and down to the waist. A belt portion 27 is secured at its front to the bottom edge of the shirt front 25 and its back is attached to the bottom edge of the back panel 25b. A slide fastener 28 is also provided for closing the adjacent ends of the belt portion 27.

Straps 29 have their outer ends attached to a portion of the belt 27 by means of stitches 30 and are adapted to have their adjacent ends adjustably connected together for adjusting the diameter of the belt portion 27 so that it may be made to rigidly support the shirt front 25.

According to the modification shown in Fig. 10 a shirt front vest constructed from a conventional vest front 31 has a conventional shirt front portion 32 inserted into the open portions thereof. Both the shirt front portion and the vest front are open from the neck portion to the waist and are adapted to be closed by buttons 33. In other respects this form of the invention is similar to that previously shown.

In Fig. 11 a modification is shown in which a provision is made for controlling the amount of the belt portion 35 which will be drawn together when the straps 36 are adjusted. These straps 36 are secured to the belt portion 35 at their outer ends and are adapted to have their inner ends adjusted for controlling the diameter of the belt portion 35. A means is provided for controlling the portion of the belt portion which will be drawn together by the straps 36. This means comprises slide fasteners 37 which have one of their stringers attached to the top edges of the straps 36 and the other of their stringers attached to an adjacent portion of the belt 35. When the slide fasteners are completely closed, as shown in Fig. 11, and the straps 36 are drawn together the vest portion 35 will only gather between the control slides 38 used for opening and closing the slide fasteners 37.

Thus the control slides 38 may be moved to any position along the length of the slide fasteners 37 to permit the waist portion to be gathered along a longer or narrower portion of the belt portion 35 when the straps 36 are drawn together.

In other respects this form of the invention is similar to the previous forms and similar parts may be identified by corresponding reference numerals.

While I have illustrated and described the pre-

ferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a man's vest a combination garment, comprising a garment front for extending from one's neck to one's waist along the front of one's body and openable from the neck down along its center, a neck portion connected with said front for extending about one's neck, a belt portion extending from the sides of said garment front at the waist line and opened at one side, and a slide fastener for closing said belt, straps attached at their outer end to said belt portion, means for adjustably attaching together the inner ends of said straps so that said inner ends may be adjusted for controlling the diameter of said belt portion for rigidly supporting said vest, and means on said straps and cooperating means on the belt portion to shorten the effective length of the straps for controlling the amount of said belt portion which will be gathered when said straps are adjusted.

2. In a man's vest a combination garment, comprising a garment front for extending from one's neck to one's waist along the front of one's body and openable from the neck down along its center, a neck portion connected with said front for extending about one's neck, a belt portion extending from the sides of said garment front at the waist line and opened at one side, and a slide fastener for closing said belt, straps attached at their outer ends to said belt portion, means for adjustably attaching together the inner ends of said straps so that said inner ends may be adjusted for controlling the diameter of said belt portion for rigidly supporting said vest, and means on said straps for controlling the amount of said belt portion which will be gathered when said straps are adjusted, said means comprising slide fasteners having one of their stringers attached to the edge portions of said straps and having the other of their stringers attached to said belt portions, and control slides for opening and closing said slide fasteners for controlling the gathered portion of said belt portion.

3. In a man's vest, straps having their outer ends attached to the back portion of said garment at the waistline, means for adjustably connecting together the inner ends of said straps so that they may be adjusted to reduce the waistline of said garment, slide fasteners having one of their stringers attached to the edge portions of said straps and the other of their stringers attached to an adjacent area of said back portion, and control slides for opening and closing said slide fasteners to control the amount of said back portion that will be gathered when said straps are adjusted to reduce the diameter of said waistline.
